REMOTE CONTROL TRANSMITTER

Melvin H. Boldt, Glenview, and Anthony J. Cascarano,
Waukegan, Ill., assignors to Zenith Radio Corporation,
a corporation of Delaware

Application November 7, 1957, Serial No. 48,358

Term of patent 14 years

(Cl. D26—14)

Fig. 1

Fig. 2

Fig. 3

Figure 1 is a perspective view of a remote control transmitter showing the new design;

Figure 2 is a front elevational view of the remote control transmitter of Figure 1; and

Figure 3 is a side elevational view of the remote control transmitter of Figure 1.

We claim:

The ornamental design for a remote control transmitter, substantially as shown and described.
